UNITED STATES PATENT OFFICE.

ARLINGTON H. MALLERY, OF SYRACUSE, NEW YORK.

HEATER.

Application filed December 8, 1921. Serial No. 520,893.

To all whom it may concern:

Be it known that I, ARLINGTON H. MALLERY, a citizen of the United States, and a resident of Syracuse, in the county of Onondaga and State of New York, have invented a certain new and useful Heater, of which the following is a specification.

This invention relates to a heater which burns a vapor generated from a liquid fuel by the heater itself, or a mixture of such vapor and air, and has for its object a particularly simple and efficient means for automatically cleaning the heater of deposits as carbon when a hydrocarbon is used, and for automatically controlling the operation of the heater.

The invention consists in the novel features, and in the combinations and constructions hereinafter set forth and claimed.

In describing this invention, reference is had to the accompanying drawings in which like characters designate corresponding parts in all the views.

Figure 1 is an elevation, partly in section, of a heater embodying my invention.

Figure 2 is a transverse sectional view on line 2—2, Fig. 1.

Figure 3 is a sectional view on line 3—3, Fig. 1.

Figure 4 is a fragmentary plan view of the burner.

Figure 5 is a fragmentary view similar to Fig. 2, showing the valve operating means as the piston operated by the pressure directly from the top of the fuel tank.

Figure 6 is a view similar to Fig. 5 showing the valve operating means as the piston has moved by a spring against the pressure of the gas in the generator.

Figure 7 is a view similar to Figs. 5 and 6 showing the pressure controlled means or piston as moved by a weight against the pressure of the gas.

This heater comprises generally, a gas generator mounted in juxtaposition to the burner to be heated thereby and having an inlet for the liquid fuel, and an outlet for the gas, and means controlled by the pressure of the gas generated in the generator for opening and closing said outlet, and for cleaning the same of deposits.

1 designates the burner which may be of any suitable form, size and construction, it being here shown as hollow and arranged in horizontal position and having upright side walls of hollow legs 2, and a horizontal

hollow top wall 3 communicating with the legs.

The legs are shown as formed with jet openings in the form of vertical slots 4 and the top wall is shown as formed with lengthwise extending jet openings or slots 5. The slots 4 are preferably formed in upright ribs 6 which form grooves or air passages 7 between them, the slots extending through the outer or top faces of the ribs, and also into the interior of the burner. The slots 5 are similarly formed in ribs 8 on the top wall of the burner. Owing to the formation of the slots 4, 5, in the ribs 6 and 8, the slots are reinforced by the ribs and held from closing by the expansion and warping of the walls of the burner when heated, and this contraction of the slots is further prevented by the cooler air passing through the grooves 7 on its way to support the combustion of the gas passing out through the slots.

9 is the generator, it being here shown as mounted above the top wall of the burner, and as having a base 10 at one end resting on the burner, the major portion thereof overhanging the burner.

The generator is preferably provided with passages 11 and 12 extending in opposite directions lengthwise thereof, and communicating at 13 at their outer ends. The inner end of the passage 11 is in communication with the fuel tank 19, and the inner end of the passage 12 being in communication with an outlet 15.

16 is a conduit connecting the outlet 15 to the interior of the burner 1, this conduit being also a mixing chamber, it having an inlet 17 for air and being shown as in the form of a goose neck, as per illustrated. The conduit 16 is suitably secured in position to receive the gas from the outlet 15. Although it is here shown as coupled to the outlet it is not necessarily coupled thereto but may have its end spaced apart from the outlet and the space between it and the outlet may serve as an air inlet.

19 is a supply tank for oil or other fuel under pressure, it communicating with the inlet 20 of the passage 11 of the generator 9 through a suitable pipe 21.

The means controlled or operated by the pressure of the gas generated in the generator 9 for controlling the outlet 15 in the illustrated form of my invention, comprises a piston having one face exposed to the pressure

of the gas in the generator and another face exposed to an opposing pressure, and a valve operated by the piston movable into and out of the passage 15.

5 25 designates the piston which is here shown as movable in a passage 26 formed in the generator in line with the outlet 15 and separated therefrom, the piston having a pin 27 projecting therefrom which terminates in 10 a needle valve 28 movable into and out of the outlet 15 which is a small jet opening. The piston passage 26 as shown in Fig. 2 is connected to the inlet and outlet end of the passages 11, 12.

15 The pressure on the piston opposed to the pressure of the gas in the generator may be provided with a spring, Fig. 6, a weight, Fig. 7 or by the pressure within the tank 19, either directly through the oil or by a pipe 29 leading from the upper part of the tank to the 20 rear end of the piston 25.

25 Preferably, as here shown, in Fig. 2, this pressure is provided by the pressure in the tank through the oil being fed from the tank by such pressure and the rear face of the piston 25 is exposed to the inlet for the oil, and a check valve 30 is provided within the passage 11 of the generator for preventing the pressure of the gas in the generator from acting upon the rear face of the piston; and in 30 the embodiment illustrated in Fig. 2, the piston also cuts off the inlet for the oil to the passage 11 when operated to open the outlet 15 by the pressure of the gas in the generator.

35 However, if desired, the check valve may be omitted and the back pressure of the gas stop the flow of the oil when such back pressure becomes greater than the pressure within the tank, in which case, the piston 25 may 40 be opened against the spring 30^a, Fig. 6, or against the pressure within the piston chamber 31 connected by the pipe 29 to the top of the tank with the piston chamber, Fig. 5.

In the construction shown in Figs. 5, 6 and 45 7, the piston chamber does not open into the inlet end of the generator but said chamber is separated therefrom by a wall and such chamber opens only into the outlet or gas pressure part of the generator.

50 In Fig. 7, the piston 33 is moved in the piston chamber 34 and is connected to a weighted lever 35 acting in opposition to the gas pressure, the lever carrying a needle valve 36 which opens and closes and cleans 55 out the outlet 37.

As shown in Fig. 2, the pipe 21 from the tank 19 is not connected directly to the inlet for the generator but to a receiver 38 having a pressure chamber 39 separated from the 60 outlet 39^a of the receiver by a partition depending from the top of the receiver and terminating near the bottom thereof. The air trapped in the chamber 39 is compressed by the fuel oil passing into the receiver and the 65 pressure of oil from the tank 19 and tends

to open the piston 25 more quickly, that is, make the operation more sensitive than when a pressure chamber is not used. The pressure within the tank 19 is maintained by a pump not shown, as a hand pump in small 70 installations and an automatically controlled power pump in larger installations.

In operation, the generator 9 is first heated as by alcohol poured on the top face of the burner and ignited, and when sufficiently hot 75 vaporizes the oil passing therethrough, and the pressure of the gas generated operates the piston 25 to open the outlet 15, whereupon the gas passes through the conduit or mixing chamber 16 where it mixes with air entering 80 at 17 and then into the hollow burner, and out through the jet openings or slots 4, 5, where it is ignited and continues to heat the generator as well as a boiler or hot air pipes, or other things to be heated.

85 When the gas is free to pass out of the outlet 15 either the piston 25 closes the inlet for the oil to the generator, or the pressure within the generator is sufficient to hold the oil from flowing into the generator. Hence, 90 after the oil in the generator has been vaporized the pressure in the generator falls and the pressure in the tank containing the oil either through the oil or directly, moves the piston 25 to close and clean out the outlet 15. 95

When the piston 25 is in this position, the oil feeds into the generator and the generator again generates gas until the pressure of the gas again moves the piston 25 to open the outlet 15, and this operation automatically repeats the piston fluctuating back and forth, automatically controlling the gas generated and cleaning out the opening 15.

What I claim is:

1. A heater comprising a burner, a generator arranged in juxtaposition to the burner to pass the gas thereto and to be heated thereby, the burner having a gas outlet, the burner also having a fuel inlet passage, the conduit connecting the fuel inlet passage and the generator, a piston movable in the passage of the burner and having one face thereof exposed to the pressure of the gas in the gas passage and its other face opposed to the pressure of the fuel, and a valve 105 operable by the piston and arranged to open and close the gas outlet of the burner, substantially as and for the purpose described.

2. A heater comprising a burner, a generator arranged in juxtaposition to the 110 burner to pass the gas thereto and to be heated thereby, the burner having a gas outlet, the burner also having a fuel inlet passage, the conduit connecting the fuel inlet passage and the generator, a piston movable 115 in the passage of the burner and having one face thereof exposed to the pressure of the gas in the gas passage and its other face opposed to the pressure of the fuel, and a valve 120 operable by the piston and arranged to open 125

and close the gas outlet of the burner, and the piston being arranged to cut off the flow of oil when operated by the gas pressure against the action of the fuel pressure, substantially as and for the purpose specified.

3. A heater comprising a burner, a generator arranged in juxtaposition to the burner to pass the gas thereto and to be heated thereby, and having an inlet for a liquid fuel, and an outlet for the gas and a piston passage, and means for closing the outlet operable by pressure of the gas in the generator to open such outlet, comprising a piston movable reciprocally in the passage having one face thereof exposed to the pressure of the gas generated whereby the piston is moved in one direction, means tending to move the piston in the opposite direction, and a valve associated with the piston and operated whereby to open and close the outlet, substantially as and for the purpose described.

4. A heater comprising a burner, a generator arranged in juxtaposition to the burner to pass the gas thereto and to be heated thereby and having an inlet for a liquid fuel, and an outlet for the gas and a piston passage, a conduit transmitting the gas from the outlet to the burner, means for closing the outlet operable by pressure of the gas generated to open such outlet, comprising a piston movable reciprocally in the passage having one face thereof exposed to the pressure of the gas in the generator whereby the piston is moved in one direction, means tending to move the piston in the opposite direction, and a valve associated with the piston and operated thereby to open and close the outlet, said valve being movable through an outlet to clean the same, substantially as and for the purpose specified.

5. A heater comprising a burner, a gas generator arranged in juxtaposition to the burner to pass the gas thereto and to be heated thereby and having an inlet for a liquid fuel and an outlet for the gas, a valve to open and close the outlet, the valve being normally arranged to close the outlet and to be opened by the pressure of the gas generated in the generator, and means whereby

the valve is moved to its closed position when the pressure of the gas falls below a predetermined amount, substantially as and for the purpose described.

6. The combination with a fuel tank, of a heater comprising a burner, a gas generator arranged in juxtaposition to the burner to pass the gas thereto and to be heated thereby and having an inlet for a liquid fuel under pressure and a passage for a piston, and an outlet for the gas, a piston slideable in said passage and having one face thereof exposed to the pressure of the gas and its other end exposed to pressure in the fuel tank, and a valve operated by the piston for opening and closing the outlet, substantially as and for the purpose specified.

7. A heater comprising a burner, a gas generator arranged in juxtaposition to the burner to pass the gas thereto and to be heated thereby and having an inlet for a liquid fuel under pressure, an outlet for the gas, and a passage for a piston in connection with the outlet, a piston slideable in the passage and having one face thereof exposed to the pressure of the gas and its other end exposed to the pressure in the fuel tank, and a valve carried by and projecting from one end of the piston and movable with the piston for opening and closing the outlet, substantially as and for the purpose set forth.

8. A heater comprising a burner, a gas generator arranged in juxtaposition to the burner to pass the gas thereto and to be heated thereby and having an inlet for the fuel under pressure, and an outlet for the gas, a valve for opening and closing the outlet, and pressure operated means for operating the valve having a face exposed to the pressure of the gas generated in the generator, and a face exposed to a pressure opposed to the gas pressure, and means for providing the opposing pressure, substantially as and for the purpose described.

In testimony whereof I have hereunto signed my name, at Syracuse, in the county of Onondaga, and State of New York, this 4th day of Nov., 1921.

ARLINGTON H. MALLERY.
